UNITED STATES PATENT OFFICE

2,418,556

SWITCH

Edward G. Miller and Ralph E. Engberg, New York, N. Y., assignors, by mesne assignments, to Allied Control Company, Inc., New York, N. Y., a corporation of New York

Application August 22, 1944, Serial No. 550,502

2 Claims. (Cl. 200—78)

1

This invention relates to switches.

An object of this invention is a switch having provision for operation into open condition with a snap action under the influence of resilient means and for being positively moved into open condition in the event that the resilient means fail to be effective.

Other objects, novel features and advantages of this invention will become apparent from the following specification and accompanying drawings, wherein:

Fig. 1 is a plan view of a switch embodying the invention;

Fig. 2 is a section on the line 2—2 of Fig. 1 in the open position of the switch;

Fig. 3 is a section on the line 2—2 of Fig. 1 in the closed position of the switch;

Fig. 4 is a section on the line 4—4 of Fig. 1, and Fig. 5 is a detail perspective.

In a box-like casing 10 of suitable insulating material there are arranged two contact units 11 and 12 respectively, each consisting of a Sylphon bellows having an end fixed to the casing and the other end movable toward and away from the fixed end to close or open a pair of contacts contained in the bellows, such a unit being covered by applicants' co-pending application, Serial No. 526,377 filed March 14, 1944. A plate 13 of conducting material rests on and is attached to the movable ends of the contact units 11 and 12. The plate 13 has its central portion downwardly offset at 14 and between the bottom of the portion 14 and the bottom of the casing 10 there is interposed an expansion spring 15 which tends to move the member 13 away from the bottom of the casing 10.

A member 16 of suitable insulating material is rotatably supported by the shaft 17 and has a part cut away to form a recess 18. The member 16 is provided with an actuating handle 19 which extends through an aperture 20 in the cover for the casing 10. A rod 21 extends through an aperture 22 in the portion 14 and is provided with a head 23 fitting into the recess 18 and pivotally held therein by a stud 24. The head 23 is of larger cross-section than the rod 21 to form an abutment or shoulder 25. A sleeve 26 is slidably mounted on the rod 21 and a spring 27 interposed between the portion 14 and the sleeve 26 biases the latter toward the shoulder 25.

A U-shaped latch member is rotatably supported by the shaft 17 and consists of two side plates 28 mounted on the shaft 17 and a cross bar 35 connecting the two side plates 28 which are located between the ends of the member 16

2

and the side walls of the casing 10. Each side member 28 or leg of the latch member is formed with two straight intersecting surfaces 29 and 30, the surfaces 29 being approximately vertical and the surfaces 30 being approximately horizontal. Additional straight surfaces 30a lead downwardly from the left ends of the surfaces 30. The sleeve 26 is provided with a pair of integral extensions 31 on each of which is mounted a roller 32 adapted for engagement with the surfaces 29, 30 and 30a in different positions of the switch. A leaf spring 33 tends to rotate the latch member 28 counterclockwise and the extent of such rotation of the latch member is limited by a stop 34. One end 15 of the spring 33 engages the cross bar 35 of the latch member 28 while the other end is fixed to a stationary bracket 36. A pin 37 extends through the lower end of the rod 21 below the bottom surface of the offset portion 14.

Fig. 2 discloses the switch in open position in which condition the handle 19 is in its leftmost position and the latch 28 is in its extreme position of counterclockwise movement and the rollers 32 engage the surfaces 29, while the member 13 is in its raised position. Clockwise movement of the handle 19 and member 16 causes initial downward movement of the rod 21 followed by a slight upward movement. The rollers 32 by engagement with the surfaces 29 cause clockwise movement of the latch 28 until the rollers clear the ends of the surfaces 29 and move onto the surfaces 30 whereupon the spring 33 brings the surfaces 30a into contact with the rollers 32. Downward movement of the pin 37 compresses the spring 27 causing the latter to force downwardly the member 13 to close the contact units 11 and 12 respectively, the force of the spring 27 overcoming the upward push of the spring 15 and the bellows members of the units 11 and 12. By engagement of the rollers 32 with the surfaces 30, the spring 27 is maintained under compression to keep the member 13 in contact-closing position, as shown in Fig. 3.

Upon counterclockwise movement of the lever 19 and member 16 from the position shown in Fig. 3, the bar 21 is returned to its original position and the latch member 28 moves counterclockwise under the influence of the spring 33 to keep the surfaces 30 and 30a engaged with the rollers 32 and thus maintain the spring 27 under contact-closing compression until the handle 19 has nearly completed its return travel during which period the shoulder 25 has been moved out of engagement with the sleeve 26. At 55 such time, the latch member engages the stop

34 whereupon the rollers 32 travel along the surfaces 30 and upon reaching the end thereof they, together with the sleeve 26, are released for upward movement under the influence of the spring 27 thereby reducing the pressure exerted by the spring 27 on the plate 13 and allowing it to be moved upwardly with a snap action to open the contact units 11 and 12. In the event that the plate 13 does not automatically move upwardly into contact-open position, it is positively pulled 10 upwardly into contact-open position by engagement of the pin 37 with the offset portion 14.

We claim:

1. In a switch, a contact operator supported for rectilinear movement between two positions, 15 resilient means biasing said contact operator toward one of said positions, an oscillatable member, a rod pivoted at one end to said member and having sliding engagement with said operator, said rod being caused to move bodily 20 relative to said contact operator upon operation of said oscillatable member, a latch pivotally supported coaxial with said oscillatable member and having two intersecting straight surfaces, a

stop to limit rotation of said latch in one direction, resilient means biasing said latch toward said stop, a sleeve slidable on said rod, an extension from said sleeve engageable with said surfaces and movable from engagement with one surface to engagement with the other surface upon operation of said oscillatable member, an abutment on said rod, and resilient means interposed between said sleeve and said contact operator biasing the former toward said abutment.

5 2. In a switch according to claim 1, a cross pin mounted in the free end of said rod for engagement with said contact operator.

EDWARD G. MILLER,
RALPH E. ENGBERG.
